E. C. MCKENZIE-MARTYN

ANTIKNOCK CARBURETOR

Filed Dec. 15, 1921

Inventor.

Edward C. McKenzie Martyn,
By his wife, Lee, Christopher Niles,
Attest

UNITED STATES PATENT OFFICE.

EDWARD C. MCKENZIE-MARTYN, OF SHORT HILLS, NEW JERSEY, ASSIGNOR TO
STANDARD DEVELOPMENT COMPANY, A CORPORATION OF DELAWARE.

ANTIKNOCK CARBURETOR.

Application filed December 15, 1921. Serial No. 522,527.

To all whom it may concern:

Be it known that I, EDWARD C. MCKENZIE-MARTYN, a subject of the King of Great Britain, residing at "Redstone," Short Hills, 5 in the county of Morris and State of New Jersey, have invented a new and useful Improvement in Antiknock Carburetors, of which the following is a specification.

This invention relates to anti-knock carburetors. It is well known that when the common motor fuels, as gasoline and kerosene, are fed to the ordinary internal combustion engine, the engine begins to knock when the compression pressure exceeds a 10 certain amount depending upon the fuel, the density of the cylinder charge and also upon certain engine factors as the shape and condition of the cylinder walls, the degree of cooling, etc. The effect of the knocking is to limit the design of the engine to a 15 low compression ratio when operated on one of these low compression fuels.

The object of this invention is to provide a means whereby the engine may have a 20 higher compression ratio and to provide against knocking by using two fuels, one a low compression fuel, as gasoline, which will be fed at low compressions, and the other a high compression fuel, as alcohol, which 25 will be automatically fed at high compressions of the engine to the partial or entire exclusion of the low compression fuel.

This I have been able to accomplish by 30 my invention, which consists of the use of two carburetor jets, each having its own mixing passage, one feeding a low compression fuel, the other a high compression fuel, the mixtures flowing in said passages being controlled by means responsive to the density of the charge in the cylinder at the end 35 of the suction stroke so that the low compression fuel mainly will be fed at high manifold vacuum and the high compression fuel mainly will be fed at low manifold vacuum and consequent high compression pressures.

Referring now to the drawings, the figure 40 is a vertical sectional view through a carburetor and intake-manifold embodying my invention.

The intake-manifold 10 is connected in the usual way to an engine (not shown) and has a throttle 11 secured on a shaft 12, which is journalled in the sides of the intake-manifold opening, extending therethrough and having a lever 13 keyed there-

on, the outer end of the lever pivotally connected to a rod 14 which is operably connected in a well known manner to the end of the throttle or to the accelerator. 60

Two passages 15 and 16 lead into the intake-manifold 10. A nozzle 17 is supplied with a low compression fuel A, such as gasoline, by well known type of a float chamber 18. 65

A similar nozzle 19 extends into the mixing passage 16 and is supplied with a high compression fuel B, such as alcohol, from a float chamber 20.

Valves 21 and 22 are secured upon shafts 70 23 and 24, respectively, in the mixing passages 15 and 16. These shafts are journalled in the sides of these passages and have secured upon their ends levers 25 and 26, which are hingedly connected by means of a rod 27, having a turn-buckle 28 therein, by means of which relative positions of the valves may be adjusted. 75

An air tight bellows 29 is carried upon a support 30 and normally held in the dotted line position, by means of a spring 31 mounted therein. This bellows is connected by means of a pipe 32 with the intake-manifold at a point posterior to the throttle 11. The movable end of the bellows 29 is connected by means of a rod 33 with the lever 26. 85

The method of operation of this device is as follows: The parts as illustrated are shown in position to cause the engine to 90 idle. At such a time, the throttle 11 is substantially closed and the vacuum in the intake-manifold 10 is very high. The bellows 29 will consequently be collapsed, as shown in full lines, thereby substantially closing 95 the valve 22 which controls the high compression mixture and holding open the valve 21 which controls the low compression mixture. Consequently the engine will be running entirely on low compression fuel. 100

As the throttle 11 is gradually opened, the vacuum in the intake-manifold 10 will gradually decrease provided the engine is maintained at a substantially constant speed. This increase in pressure in the 105 intake-manifold will permit the bellows 29 to open somewhat under the action of the spring 31, thereby partially closing the valve 21 correspondingly opening the valve 22. The engine will then receive a 110 charge, which is made up partially of the high compression mixture and partially of

the low compression mixture, the proportion of each depending upon the relative positions of the valves 21 and 22, which with any given setting will depend upon the degree of vacuum in the intake-manifold.

With the throttle 11 substantially wide open the vacuum in the intake-manifold will be so low that the bellows 29 will be forced by the spring 31 to the open position, thereby moving the valve 21 to substantially a closed position and opening wide the valve 22. The engine will then be receiving a charge, which is made up almost wholly of the high compression mixture.

15 While I have shown and described certain embodiments of my invention, it is to be understood that it is capable of many modifications. Changes, therefore, in the construction and arrangement may be made 20 without departing from the spirit and scope of the invention as disclosed in the appended claims, in which it is my intention to claim all novelty inherent in my invention as broadly as possible in view of the prior 25 art.

What I claim as new and desire to secure by Letters Patent is:

1. In combination, an internal combustion engine having an intake-manifold, a throttle 30 therein, two passages leading to said intake-manifold anterior to the throttle valve, a nozzle in one passage connected to a source of low compression fuel, a nozzle in the other passage connected to a source of high compression fuel, and means responsive to the 35 density in the engine cylinder at the end of the suction stroke for gradually decreasing the proportion of the low compression mixture and increasing the proportion of the 40 high compression mixture, as said density increases, and vice versa as the density decreases.

2. In combination, an internal combustion engine having an intake-manifold, a throttle 45 therein, two passages leading to said intake-manifold anterior to the throttle valve, a nozzle in one passage connected to a source of low compression fuel, a nozzle in the other passage connected to a source of high compression fuel, a valve in each passage and 50 means operably connected to said valves and operable by changes in the vacuum of the manifold for gradually shifting from a low compression mixture to a high compression mixture as the vacuum in the intake-manifold 55 decreases, and vice versa as the vacuum increases.

3. In combination, an internal combustion engine having an intake-manifold, a 60 throttle therein, two passages leading to said intake-manifold anterior to the throttle valve, a nozzle in one passage connected to a source of low compression fuel, a nozzle in the other passage connected to a source of high compression fuel, a valve 65 to a source of high compression fuel, a valve

in each passage and a bellows operably connected to said valves and operable by changes in the vacuum of the manifold to close the valve in the low compression passage and open the valve in the high compression passage as the vacuum in the manifold decreases.

4. In combination, an internal combustion engine having an intake-manifold, a throttle 75 therein, two passages leading to said intake-manifold anterior to the throttle valve, a nozzle in one passage connected to a source of low compression fuel, a nozzle in the other passage connected to a source of high compression fuel, a valve in each passage, a bellows operably connected to said valves and operable by changes in the vacuum of the manifold to close the valve in the low compression passage and open the valve in the high compression passage as the vacuum in the manifold decreases, and a spring for normally holding open the valve in the low compression passage.

5. In combination, an internal combustion engine having an intake-manifold, a throttle 90 therein, two passages leading to said intake-manifold anterior to the throttle valve, a nozzle in one passage connected to a source of low compression fuel, a nozzle in the other 95 passage connected to a source of high compression fuel, a valve in each passage, a bellows operably connected to said valves and operable by changes in the vacuum of the manifold to close the valve in the low compression passage and open the valve in the high compression passage as the vacuum in the manifold decreases, and a spring for normally holding open the valve in the low compression passage and for holding substantially closed the valve in the high compression 100 passage.

6. In combination, an internal combustion engine having an intake-manifold, a throttle 110 therein, two passages leading to said intake-manifold anterior to the throttle valve, a nozzle in one passage connected to a source of low compression fuel, a nozzle in the other passage connected to a source of high compression fuel, a valve in each passage, means 115 operably connected to said valves and operable by changes in the vacuum of the manifold for gradually shifting from a low compression mixture to a high compression mixture as the vacuum in the intake-manifold decreases and means for adjusting the relative positions of said valves.

7. In combination, an internal combustion engine having an intake-manifold, a throttle 125 therein, two passages leading to said intake-manifold anterior to the throttle valve, a nozzle in one passage connected to a source of low compression fuel, a nozzle in the other passage connected to a source of high compression fuel, a valve in each passage, means 130 operably connected to said valves and

responsive to changes in the density of the cylinder charge at the end of the suction stroke for gradually shifting from a low compression mixture to a high compression mixture as the vacuum in the intake-manifold decreases and means for adjusting the relative positions of said valves.

8. A carburetor for internal combustion engines comprising an intake tube, a throttle valve therein, two passages leading to said tube anterior to the throttle, a nozzle in one passage adapted to be connected to a source of low compression fuel, a nozzle in the other passage adapted to be connected to a source of high compression fuel, and means responsive to the vacuum of the tube for gradually decreasing the proportion of the low compression mixture and increasing the proportion of high compression mixture, as the vacuum decreases, and vice versa as the vacuum increases.

9. A carburetor for internal combustion engines comprising an intake tube, a throttle valve therein, two passages leading to said tube anterior to the throttle, a nozzle in one passage adapted to be connected to a source of low compression fuel, a nozzle in the

other passage adapted to be connected to a source of high compression fuel, a valve in each passage, vacuum controlled means operably connected to said valves and operable by changes in the vacuum of the tube for gradually shifting from a low compression mixture to a high compression mixture as the vacuum in the tube decreases and vice versa as the vacuum increases.

10. A carburetor for internal combustion engines comprising an intake tube, a throttle valve therein, two passages leading to said tube anterior to the throttle, a nozzle in one passage adapted to be connected to a source of low compression fuel, a nozzle in the other passage adapted to be connected to a source of high compression fuel, a valve in each passage, vacuum controlled means operably connected to said valves, and a pipe leading from said vacuum controlled means to a point in said tube posterior to said throttle for gradually shifting from a low compression mixture to a high compression mixture as the vacuum in the tube decreases and vice versa as vacuum in the tube increases.

EDWARD C. MCKENZIE-MARTYN.
